UNITED STATES PATENT OFFICE.

LAWRENCE L. MORRIS, OF BALLSTON SPA, NEW YORK.

PAPER-MAKING MACHINE.

1,359,520.

Specification of Letters Patent. Patented Nov. 23, 1920.

Application filed January 29, 1920. Serial No. 354,948.

To all whom it may concern:

Be it known that I, LAWRENCE L. MORRIS, a citizen of the United States, residing at Ballston Spa, in the county of Saratoga and 5 State of New York, have invented certain new and useful Improvements in Paper-Making Machines, of which the following is a specification.

My invention relates to machines for 10 making paper and the objects of my invention are to provide a paper making machine on which can be made a wide variety of papers, varying in thickness from thin tissue to straw wrappers, which will not require 15 the use of web carriers of either wire or felt, and which will also crimp the thinner papers if so desired.

I accomplish these objects by means of 20 the machine illustrated in the drawing which is a side elevation of my machine, partly in section, and also shows a portion of a calender machine.

Referring to the drawing, A, represents 25 the frame of the machine, B, represents the tank which is of the usual form and construction, and provided with a stock inlet F. and a flow-off B².

Mounted in the frame of the machine and 30 projecting into the tank B, in the usual manner, is the web-forming rotating suction cylinder C, which may be of any desired type or construction.

Mounted above the suction cylinder C, at 35 or near the point where the suction is released, I mount a jacket-roll D, provided with a guard board E. Suitably mounted in the tank B. is a dandy roll Y.

In the frame A. I mount the suction rolls 40 J, N and Q. Above the suction rolls J, and N, respectively, I mount the rollers K and O, adapted to rest upon the suction rolls or upon the web or paper passing over said suction rolls. M, P, and U, are guide rolls one of which is mounted beside each of the 45 before mentioned suction rolls.

Above the suction roll Q. I mount the couch roll R, provided with a guard board S.

Adjoining the couch roll R. I mount a 50 hot press roll T, adapted to press against the couch roll; and adjacent to said hot press roll I mount a doctor Z, adapted to be adjusted so that paper after it passes over the hot press roll T. will drag over the edge thereof and be crimped thereby.

55 I preferably mount between the suction cylinder C. and the suction roll J. the brush

roll G, with a suitable guard H, said brush adapted to clean the foraminated cover of the suction cylinder.

Suitable sprinkling pipes s. are also provided to clean the surface of the various suction rolls.

The usual means for driving the rotating parts of the machine, and the customary suction and water pipes, are, of course, provided—though none of them are shown.

The operation of my machine is as follows: Stock is forced through the pipe F. into the lower chamber of the tank B. and flows, as indicated by the direction darts, 70 into contact with the web-forming suction cylinder C. The excess flow of stock escapes through the flow-off B². The dandy roll Y. smooths out and slightly compacts the web X, which has been formed on the surface 75 of the suction cylinder C. The web X. then passes under the jacket roll D, which further compacts the web, squeezes out a portion of the water contained therein, and picks it off of the web-forming cylinder. 80

The web then passes over the suction roll J, under the guide roll M, over the suction roll N, under the guide roll P. It then passes between the suction roll Q. and the couch roll R, under the guide roll U, between the couch roll R. and the hot press roll T. and then to the press set of the calender machine.

If it is desired to crimp the paper, the doctor Z. is adjusted so that in passing from the 90 hot press roll T. to the calender press set, the web X. is caused to drag over the edge of the doctor. This dragging will cause the desired crimp.

In running some of the heavier papers, 95 such as straw wrappers, it is unnecessary to run the web over the hot press roll T, and in such cases the web X, after it passes the guide roll U, passes directly to the calender press set, as indicated by dotted lines.

A machine arranged as shown and described will make successfully a wide variety of papers, from "tissue" to "straw wrappers"; will crimp the lighter papers without the substitution of parts of the machine, and using no web carriers it is extremely economical, both in first cost and in upkeep.

What I claim as new and desire to secure by Letters Patent is:

1. In a paper making machine, a frame; a tank adapted to contain paper pulp; a

rotating web-forming suction cylinder mounted in said tank; a jacket roll mounted above and adapted to co-act with said suction cylinder; a series of suction rolls mounted in said frame; a couch roll mounted above and adapted to co-act with the suction roll at the end of said series farthest from said suction cylinder; idler rolls mounted above and adapted to co-act with the remainder of 10 said series; and guide rolls, one following each of said suction rolls.

2. In a paper making machine, a frame; a tank adapted to contain paper pulp; a rotating web-forming suction cylinder mounted in said tank; a jacket roll mounted above and adapted to co-act with said suction cylinder near the point where the suction releases; a dandy roll mounted adjacent to said suction cylinder; a series of suction 15 rolls mounted in said frame; a couch roll mounted above and adapted to co-act with the end roll of said series farthest from said suction cylinder; idler rolls mounted above and adapted to co-act with the remainder 20 of said series; a guide roll following each 25

of said suction rolls; guard boards, mounted over said jacket roll and said couch roll.

3. In a paper making machine, a frame; a tank adapted to contain paper pulp; a rotating web-forming suction cylinder mounted 30 in said tank; a jacket roll mounted above and adapted to co-act with said suction cylinder; a series of suction rolls mounted in said frame; idler rolls mounted above and adapted to co-act with each of said series, 35 except the one farthest from said suction cylinder; a couch roll mounted above and adapted to co-act with the suction roll before excepted; guide rolls, one following each of said suction rolls; a hot press roll mounted 40 adjacent to and adapted to co-act with said couch roll; and a doctor mounted adjacent to said hot press roll, all substantially as shown and for the purposes set forth.

In testimony whereof I have affixed my 45 signature in the presence of two witnesses.

LAWRENCE L. MORRIS.
